US0D1041871S

(12) **United States Design Patent** (10) Patent No.: **US D1,041,871 S**
(45) Date of Patent: ** Sep. 17, 2024

(54) BAG	(56)	References Cited
(71) Applicant: YETI Coolers, LLC , Austin, TX (US)		U.S. PATENT DOCUMENTS
(72) Inventors: Roy Joseph Seiders , Austin, TX (US); Dustin Bullock , Austin, TX (US)	1,001,729 A 1,113,757 A 1,305,797 A 1,378,928 A 1,386,557 A D107,596 S 2,188,899 A 2,483,802 A 2,499,291 A 2,548,064 A 2,575,191 A 2,771,112 A 2,871,900 A 2,954,891 A 3,121,452 A 3,297,119 A *	8/1911 Buchanan et al. 10/1914 Crutcher et al. 6/1919 Henderson 5/1921 Witzel 8/1921 Dusquesnoy 12/1937 Felmann 2/1940 Tebbard et al. 10/1949 Vonbun et al. 2/1950 Mogil 4/1951 Mogil et al. 11/1951 Seipp 11/1956 Ingram 2/1959 Auditore 10/1960 Imber 2/1964 Hyman 1/1967 Viol A47D 1/02 150/108
(73) Assignee: YETI Coolers, LLC , Austin, TX (US)		
(*) Notice: Patent file contains an affidavit/declaration under 37 CFR 1.130(b).		
(**) Term: 15 Years		
(21) Appl. No.: 29/794,355		
(22) Filed: Jun. 11, 2021		
Related U.S. Application Data		
(63) Continuation of application No. 29/739,007, filed on Jun. 22, 2020, now Pat. No. Des. 923,323, which is a continuation of application No. 29/663,667, filed on Sep. 18, 2018, now Pat. No. Des. 887,699.

CLAIM

The ornamental design for a bag, as shown and described.

DESCRIPTION

FIG. 1 is a top, front, left perspective view of a bag showing our new design;

FIG. 2 is a front view thereof;

FIG. 3 is a rear view thereof;

FIG. 4 is a left side view thereof; and,

FIG. 5 is a right side view thereof.

The dash broken lines depict portions of the bag that form no part of the claimed design. The shorter dash broken lines

depict stitching that forms no part of the claimed design. The zig-zag broken lines represent stitching that forms no part of the claimed design.
